UNITED STATES PATENT OFFICE

ROBERT DUNCAN COMRIE, OF SOUTHAMPTON, ENGLAND

DISPENSING DEVICE

Application filed May 17, 1928, Serial No. 278,481, and in Great Britain June 8, 1927.

This invention relates to the removal of powder, crystals, paste, liquids and like fluid, semifluid or plastic substances, hereinafter referred to as powder, from containers in regulated or measured quantities so as to produce at will a layer of substantially uniform thickness of the powder or a desired quantity of the same which can be taken up by means of a brush, pad, cloth or the like, or be otherwise removed.

According to my invention, there is provided, in combination with a container for powder, a band or strip of material which is adapted to receive a layer or quantity of powder on its upper surface and to be moved into the container to receive such charge of powder and to be withdrawn from such container, so as to bring the charge of powder into position to permit of its being conveniently removed therefrom by means of a brush or other suitable device. For example, the band or strip can be normally retained in the interior of the container by means of a spring, in which case the band or strip and the spring may be formed integrally with one another of soft vulcanized india rubber. Means may be provided for holding the band or strip in its withdrawn position during the removal of powder.

The band or strip is advantageously provided with a projection which, when said band or strip is in its retracted position, serves to close the aperture in the container through which the band or strip passes, so as to prevent the escape of the powder when the device is not in use.

In the accompanying drawings, I have shown how my said invention may be conveniently and advantageously carried into practice. In these drawings

Figure 1 is a side elevation of one form of my device, showing the band or strip in its retracted position;

Figure 2 shows the same with the band or strip in its extended position; and

Figure 3 is a section on the line III—III, Figure 1.

Figure 4 is a side elevation and

Figure 5 a section on the line V—V, Figure 4, showing a modification.

Figures 6 and 7 are side elevations of another modification showing the band or strip in its retracted and extended positions respectively.

Figures 8 and 9 are side elevations of further modifications shown with the bands or strips in the extended position.

Figure 10 is a side elevation and

Figure 11 a transverse section on the line XI—XI, Figure 10 showing a still further modification.

In Figures 1, 2 and 3 there is provided within the container A a band or strip B of elastic india-rubber or other suitable material, which has a suitably shaped cavity C provided with protuberances D, D on its inner surface. The innermost part E of the strip is made thinner, so as to form a spring 70 and extends beneath a bridge piece F in the container, a projection E' being provided on the spring piece E to anchor it in the container. The other end of the strip B extends to the exterior through a slot G in the peripheral wall of the container. The slot G is made of such width as to permit the passage to the exterior of a layer or quantity of powder on or contained by the surface of the band or strip B. The outer end of the strip is provided with an enlarged portion H that normally serves to close the slot and has an extension H' adapted to be grasped by the hand. When so withdrawn, the outer end of the strip can be secured on the top 85 of the container by means of a projection J on the container engaging a hole H'' in the extension H' in such a manner that the surface bearing or containing the layer of powder lies over the curved peripheral surface of 90 the container in a substantially horizontal position as shown in Figure 2, so as to enable the powder to be taken off by means of a concave surfaced brush or pad. The enlarged end H, H' of the strip, which serves 95 both as a closing device and as a handle, may be formed integrally with the strip as shown, or it may be formed separately and suitably secured thereto. The inner end of the strip may also be clamped between two metal sur-

100

faces riveted together and to a wall of the container, or it may be held in any other suitable manner.

In the arrangement shown in Figures 4 and 5 the strip is arranged so as to extend substantially parallel to the upper wall K' of the container K at a short distance therefrom, so that when there is only a small quantity of powder in the container, such powder can be brought by gravity on to such wall, and then by rapidly inverting the container is allowed to fall on to the elastic band or other material and be drawn out for use. In this form, the strip B is drawn out from the container by means of a bent lever L pivotally mounted at M on the container K. The facility of removing the last quantity of powder can be increased by making the container oval in cross-section and arranging the band perpendicular to the major axis of the oval near the curve of smallest radius of curvature. Instead of using a band formed wholly of india rubber, a band formed partially of rubber can be employed, the inside piece of rubber being arranged to serve as a spring and the outside end being made in the form of a spoon or any other shaped container, *e. g.*, of tin. This may be used as a measure or device for ensuring regulated deliveries of material.

In Figures 6 and 7, the band is extended by means of a metal strip N having an extension O hinged thereto at O' and provided with a finger-piece P. Suitable guides can be provided in the container for the strip N.

Figures 8 and 9 show modifications wherein a double band B' is arranged in two containers Q', Q' and Q, Q, respectively, having their lower parts pivotally connected at R.

In Figures 10 and 11, an endless band S of flexible or elastic material is arranged to extend over rollers T, T' arranged inside the container and over a curved surface V outside the container, a milled head W being provided for turning one of the rollers T', which may be advantageously roughened, ribbed or fluted in such a manner as to engage the band and to bring parts thereof to the exterior in a convex position in order to permit of the powder being conveniently removed therefrom. If desired, the roughened, ribbed or fluted roller T' may be made of larger diameter than the roller T. Y is a cover hinged to the container body X.

The elastic or flexible bands above mentioned may be advantageously formed of soft vulcanized india rubber of any colour or colours.

The quantity of material delivered by the bands may be regulated by means of pads or rollers of rubber or other suitable materials affixed at the slots or elsewhere as found convenient such pads or rollers rubbing or running on the bands with a regulated squee-

gee effect as the bands emerge from their containers. A similar device may be employed as the bands enter the containers for the purpose of cleansing the same.

I claim:

1. A receptacle for powder, comprising a container provided with a slot, a strip of elastic material adapted to receive a layer of powder on its upper surface and having its inner end secured within the container so as to be movable through the slot into and out of said container, and means for securing the inner end of said strip of material to the wall of the container.

2. A receptacle for powder, comprising a container provided with a slot, a strip of material movable into and out of said container through the slot therein and adapted to receive a layer of powder on its upper surface, and a longitudinally extended piece of elastic material secured at one end thereof to the wall of the container and adapted to retain normally the strip of material within the container and to prevent the complete withdrawal of said strip of material from said container.

3. A receptacle for powder, comprising a container provided with a slot, a strip of material movable into and out of said container through said slot and adapted to receive a layer of powder on its upper surface and an elastic member by means of which the strip of material is connected to and returned to the interior of said container after withdrawal, said elastic member being formed integrally with said strip of material and having one end thereof connected to the interior of the container.

4. A receptacle for powder comprising a container provided with a slot, a strip of material movable into and out of said container through the said slot, and a thin strip of soft vulcanized india rubber formed integrally with said strip of material and secured to the said container normally to retain the strip of material within said container and to prevent the complete withdrawal of the said strip of material from said container.

5. A receptacle for powder comprising a container provided with a slot, a strip of material movable into and out of said container through the said slot, a thin strip of soft vulcanized india rubber formed integrally with said strip of material and secured to the said container normally to retain the strip of material within said container and to prevent the complete withdrawal of the said strip of material from said container and a projection carried by said strip of material to close the slot in the container when the said strip of material is in its retracted position.

6. A receptacle for powder, comprising a container provided with a slot, a strip of material for receiving powder movable into and out of said container through said slot, means

for withdrawing the strip of material from said container, a longitudinally extended piece of elastic material for preventing complete withdrawal of the strip of material receiving the powder from the container and for returning the strip of material into the interior of said container after withdrawal, and means for closing the slot in said container when the strip of material is returned to the interior of the container.

10 7. A receptacle for powder comprising a container provided with a slot, a strip of material movable into and out of said container through said slot, means for withdrawing the strip of material from said container, and a thin strip of soft vulcanized india rubber formed integrally with said strip of material to prevent the complete withdrawal of said strip of material from the said container.

15 8. A receptacle for powder comprising a container provided with a slot, a strip of material movable into and out of said container through said slot, means for withdrawing the strip of material from said container, a thin strip of soft vulcanized india rubber formed integrally with said strip of material to prevent the complete withdrawal of said strip of material from the said container, and a projection carried by said strip of material to close the slot in the container when the said strip of material is in its retracted position within the container.

20 9. A receptacle for powder comprising a container provided with a slot, a strip of material movable into and out of said container through said slot, a handle attached to said strip of material to facilitate withdrawal from the container, a spring for normally retaining the strip of material within said container, and means for maintaining said strip of material in position outside said container against the action of said spring.

25 10. A receptacle for powder comprising a container provided with a slot, a strip of material movable into and out of said container through said slot, a handle attached to said strip of material to facilitate withdrawal from the container, a thin strip of soft vulcanized india rubber formed integrally with said strip of material to prevent the complete withdrawal of said strip of material from said container, and means for maintaining said strip of material outside said container against the action of said strip of soft vulcanized india rubber.

30 11. A receptacle for powder comprising a container provided with a slot, a strip of material movable into and out of said container through said slot, a handle attached to said strip of material to facilitate withdrawal from the container, a thin strip of soft vulcanized india rubber formed integrally with said strip of material to prevent the complete withdrawal of said strip of material from said container, means for maintaining said

strip of material outside said container against the action of said strip of soft vulcanized india rubber, and a projection carried by said strip of material to close the slot in the said container when the said strip of material is in its retracted position within the container.

35 12. A receptacle for powder comprising a container provided with a slot, a strip of material movable into and out of said container through said slot, a handle attached to said strip of material to facilitate withdrawal from the container, a spring consisting of a thin strip of soft vulcanized india rubber formed integrally with said strip of material and secured to the said container normally to retain the strip of material within said container and to prevent the complete withdrawal of said strip of material from said container, a projection on the exterior of said container adapted to engage a hole in the handle attached to said strip of material to maintain said strip of material withdrawn from said container against the action of said india rubber spring and a projection carried by said strip of material to close the slot in said container when the strip of material is in its fully retracted position within the container.
